UNITED STATES PATENT OFFICE.

HARRY KANTOR, OF RIMERSBURG, PENNSYLVANIA.

MATCH-DISPENSING RECEPTACLE.

Application filed March 15, 1923. Serial No. 625,325.

To all whom it may concern:

Be it known that I, HARRY KANTOR, a citizen of Hungary, residing at Rimersburg, in the county of Clarion and State of Pennsylvania, have invented certain new and useful Improvements in Match-Dispensing Receptacles, of which the following is a specification.

This invention relates to certain new and useful improvements in match dispensing receptacles and particularly to that type wherein a single match is delivered for the user, and has for its primary object to provide a delivery shaft or drum that receives a single match from a superposed receptacle for delivering the same upon a tray disposed outwardly of the receptacle casing. The invention further includes means for preventing a reverse rotation of the delivery drum after the same has received a single match for delivery, it being understood that the device may as well be employed for the dispensing of tooth picks or similar articles.

With the above and other objects in view as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a front elevational view of a match dispensing receptacle constructed in accordance with the present invention,

Figure 2 is a vertical longitudinal sectional view taken on line II—II of Fig. 3,

Figure 3 is a vertical cross-sectional view taken on line III—III of Fig. 1 showing the match delivery drum disposed beneath the match receptacle, the wire rack for receiving the match and the device to prevent opposite rotation of the delivery drum,

Figure 4 is a horizontal sectional view taken on line IV—IV of Fig. 1 showing the slotted opening in the bottom wall of the match receptacle,

Figure 5 is a perspective view of the wire support for the delivered matches, and

Figure 6 is a perspective view of the spring arm to prevent reverse rotation of the delivery drum.

Referring more in detail to the accompanying drawing, there is illustrated a match dispensing receptacle embodying a

base plate 1 supporting a casing having front and rear walls 2 and 2^a respectively, end walls 3 and 4 a removable cover wall 5.

A match receptacle is disposed within the casing adjacent the transverse median line thereof and is formed of side plates 6 secured to the front and rear walls 2 and 2^a of the casing with the lower ends thereof curved inwardly in directions toward each other with the adjacent edges slightly spaced to provide a restricted opening for the passage of a single match 7 as shown in Fig. 3. A delivery drum for singly feeding matches exteriorly of the casing is horizontally journaled within the casing beneath the match receptacle, a pair of bracket bearings 8 supported on the base plate 1 interiorly of the casing having a shaft 9 journaled therein with one end of the shaft projecting through the end wall 4 of the casing and provided with an operating knob 10 as illustrated. The central portion of the shaft 9 supports the delivery drum 11 that is disposed centrally within the casing from the opposite end walls 3 and 4 and is provided with reduced ends 12 adjacent the bracket bearings 8 for purposes presently to appear, the drum 11 being provided with diametrically opposite longitudinally extending match receiving grooves 13 shown more clearly in Fig. 3.

A support is provided for receiving the match when delivered by the drum 11, the support being formed of a wire frame 90 shown more clearly in Fig. 5 embodying V-shaped side legs 14 that extend through a slotted opening 15 in the front wall 1 of the casing, the inner ends of the V-shaped legs 14 carrying depending extensions 16 within the casing that are connected at their lower ends by a cross rod 17 that engages the base plate 1, the outer ends of the V-shaped legs 14 carrying depending extensions 18 provided with barbs 19 upon the lower ends thereof to be anchored within the front face of the base plate 1 as shown in Fig. 3, lateral movement of the V-shaped legs 14 being prevented by the inner sections of said legs extending into notched portions 15^a provided in the bottom wall of the slot 15 in the front wall of the casing 2. The match receiving legs 14 are so disposed as to prevent the inner edges thereof at their points of connection with the depending portions 16 for engagement with the reduced end portions 12 of the drum 11.

To prevent a reverse movement or rotation of the drum 11, a spring arm 20 shown in detail in Fig. 6 is provided with an angle end 21 that is secured to the inner face of the front wall 2 has the casing adjacent the lower end thereof, the free ends 22 of the spring arm riding over the periphery of the drum 11 and adapted to be received in the grooves 13 as shown in Fig. 3.

From the above detail description of the device, it is believed that the construction and operation thereof will at once be apparent, it being noted that matches 7 or similar articles, such as tooth picks are placed in the receptacle by removing the cover 5, and a single match will project through the opening between the adjacent edges of the side plates 6 of the receptacle to ride upon the drum 11 until a notch or groove 13 is aligned with said opening. Upon rotating the drum by the handle 10, in the direction indicated by the arrow in Fig. 3, the single match 7 is delivered onto the V-shaped arms 14 of the support, the match being delivered through the opening 15 in the front wall of the casing for use. The spring arm 20 engaging the lower side of the drum 11 and freely riding over the surface thereof has the end 22 projected into a groove 13 in the manner as shown in Fig. 3 which will prevent a reverse rotation of the drum and prevent matches or similar articles from falling into the lower end of the casing at the rear side thereof.

While there is herein shown and described the preferred embodiment of the present invention, it is nevertheless to be understood that minor changes may be made therein without departing from the spirit and scope of the invention as claimed.

What is claimed as new is:—

1. In a match dispensing apparatus, a casing, a match receptacle in the casing hav-

ing a delivery slot in the lower end thereof, a delivery drum journaled in the casing beneath the receptacle, a match receiving support extending through a wall of the casing to receive a match from the drum, said match receiving support being formed of a single strand of wire having spaced V-shaped side legs extending through an opening in the casing to receive a match, the inner ends of the legs carrying depending extensions connected at their lower ends by a cross rod engaging the base of the casing, and the outer ends of the legs carrying depending extensions having barbs formed on their ends anchored in the outer edge of the casing base.

2. In a match dispensing apparatus, a casing, a match receptacle in the casing having a delivery slot in the lower end thereof, a delivery drum having diametrically opposed match receiving grooves in the periphery thereof adapted to register with the delivery slot in the receptacle and journaled in the casing beneath the receptacle, a match receiving support extending through a wall of the casing to receive a match from the drum, a spring arm having the free end thereof engaging the periphery of the drum and adapted to be received in the drum grooves to prevent reverse rotation thereof, said match receiving support being formed of a single strand of wire having spaced V-shaped side legs extending through an opening in the casing to receive a match, the inner ends of the legs carrying depending extensions connected at their lower ends by a cross rod resting upon the base of the casing, and the outer ends of the legs carrying depending extensions having barbs at their ends anchored in the outer edge of the casing base.

In testimony whereof I affix my signature.

HARRY KANTOR.
